UNITED STATES PATENT OFFICE

HERMANN STEINHART, OF STUTTGART, GERMANY, ASSIGNOR TO ROBERT BOSCH
AKTIENGESELLSCHAFT, OF STUTTGART, GERMANY

ELECTRIC SWITCH

Application filed February 17, 1931, Serial No. 516,406, and in Germany February 26, 1930.

The present invention relates to electric switches and in particular is applicable to switches used in the electric systems of motor vehicles.

5 In order to provide a switch of compact construction suitable for use with the electric systems of motor vehicles, it has already been proposed to provide a withdrawable key member the displacement of which member 10 is utilized for an ignition circuit whilst the switch handle in the axis of which the key is adapted to be mounted is utilized for the lighting circuit. In one known form of construction, the lighting switch is unlocked by 15 pressing down the key against an axially movable pin, which simultaneously switches on the ignition. The ignition is switched off and the lighting switch simultaneously locked by the withdrawal of the key.

20 According to the present invention and in order, for example to allow locking of the lighting switch, when the switch key is withdrawn, the switch key is automatically coupled to a rotatable switch member when it 25 is rotated while in the "pressed down" position, it being possible to make and break at least one circuit by the rotation of this switch member.

The invention is more particularly described with reference to the accompanying drawing which illustrates one form of construction by way of example and in which:—

Figure 1 is a longitudinal section through the switch.

25 Figure 2 is a cross section on the line AB of Figure 1.

Figure 3 is a detail view of one of the discs receiving the key.

Figure 4 is a detail view showing another 40 disc for receiving the key.

Figure 5 is a detail view of the key and

Figure 6 is a circuit diagram for one switch disc.

45 Three lugs or flanges 2, of a pot-shaped member 3 which is provided with a rotatable sleeve 4 for a key 5, are riveted to a base plate 1 made of insulating material. The top of the sleeve 4 is covered by two discs 6 and 7 bordered into the sleeve, the disc 6 having 50 slots 8 formed therein whilst the disc 7 has

slots 9 for the reception of the wards 10 of the key 5. The bottom of the sleeve 4 is connected to a circular switch plate 11.

An annular switch plate 12 which is connected to a hollow knob 13 adapted to be used 55 as a handle is disposed around this switch plate 11. As shown in Fig. 1, the connection between switch plate 12 and knob 13 comprises an annular plate 12^a secured to switch plate 12 and connected by rivets or similar 60 fastening means 12^b to knob 13, said rivets passing through arcuate slots (not shown) provided in the pot-shaped member 3. The two switch plates 11, 12 are provided on their lower sides with suitable contact segments 23. 65

A bolt 14, which is connected at one end by a bar 15 to a pin 16, is axially displaceable relative to the sleeve 4 within which it is mounted, such displacement being against a helical spring 17 when the key 5 is pressed 70 down against the bolt. The two switch plates 11 and 12 are provided on their co-operating adjacent edges with notches 18, 19 respectively, the number of notches corresponding to the number of switch positions. 75 In every switch position of the two switch plates 11, 12 one notch 18 and one notch 19 lie opposite each other, so that the pin 16 can be accommodated between them.

A bolt 20 adapted to move in a longitudinal 80 direction is mounted in a bore of the base plate 1 and serves for guiding the pin 16. Two stop pins 21 are mounted in the base plate 1 for the purpose of limiting the rotations of the two switch plates 11, 12. Contact springs 22, which are secured to the base plate 1 and are connected in suitable manner to the leads of the electric systems, abut against the lower side of the two switch plates 11, 12. 85

The operation of the switch is as follows:— 90

When the key 5 is drawn out of the sleeve 4 the bar 15 on the bolt 14 is pressed against the switch plate 11 by the spring 17 as shown. The pin 16 thereby engages in two mutually opposite notches 18 and 19 of the two switch 95 plates 11 and 12, and these accordingly are secured against rotation as the pin 16 forms a locking connection between the plates.

For the purpose of using the switch, the key 5 is inserted in the sleeve 4 whereby the 100

key-ward 10 passes through the two slots 8, disposed in juxtaposition in the two discs 6 and 7. By pressing the key 5 against the bolt 14 the locking pin 16 is forced out of the two grooves 18 and 19, whereby the two switch plates 11, 12 are unlocked, so that they can be rotated into any desired switch position.

If the key 5 is rotated to some degree in its "pressed down" position it is maintained in this position by the lower face of the disc 7 against which the key-ward 10 abuts. The key 5 is preferably rotated until the key-ward 10 reaches and is inserted in the slots 9 of the disc 7, these slots being covered by the disc 6. The key 5 thus becomes coupled with the sleeve 4 and with the switch plate 11 connected to this. If the key is now rotated further for 90°, the switch plate 11 will also be displaced for 90° so that a certain circuit or circuits for example the ignition and horn circuit may be switched in.

This position of the switch plate 11 is illustrated in Figure 6 in which two contact segments of the switch plate 11 are represented by 23, the contact springs by 22, the battery by 24, the ignition device by 25 and the horn by 26. In this position the key 5 can be withdrawn and the switch thereby locked.

When it is desired to bring the switch plate 11 back into the initial position, the key 5 is inserted and pressed against the bolt 14 so that the key-ward 10 can come within the slots 9 in the disc 7 and the key 5 is then turned back until it can again come out of the sleeve through the slots 8 of the discs 6 and 7 the slots lying one above the other. In this position the ignition circuit in addition to the horn circuit is interrupted.

The switch plate 12 serves for switching the lighting on and off, and has three positions as known: (1) "off" (2) "parking light" and (3) headlights. It can be locked in any of these three switch positions by withdrawing the key 5.

If desired the lighting switch can be changed in any suitable manner; this also applies to the general construction of the whole switch. If the switch is only to work the horn circuit and not the ignition circuit as described, the contact springs 22 provided on the switch plate 11 for the ignition circuit are omitted.

What is claimed is

1. An electric switch comprising a pair of relatively displaceable elements, contacts on said elements, a fixed member, contacts on said fixed member adapted to be engaged by the contacts on said relatively displaceable members, means including a pin carried by said fixed member for locking said relatively displaceable members in a fixed relative position, and means removable from the switch for displacing said locking means to permit

relative displacement of said members on insertion of said removable means.

2. An electric switch comprising a housing, a pair of co-axial annular relatively displaceable elements, contacts carried by said elements, a fixed plate, contacts on said fixed plate engaged by contacts on said annular elements to establish a number of independent electric circuits, a pin carried by said fixed plate which normally prevents said annular elements from relative displacement and a key which, on insertion within said housing displaces said pin from locking engagement with the annular elements, one of which is rotated relatively to the other on rotation of the key.

3. An electric switch comprising a housing, a base plate at one end of said housing, contacts on said base plate, a sleeve within said housing, an annular plate connected to said sleeve and having a number of slots on its outer periphery, a second annular plate co-axial with the first plate and slotted on its inner periphery, contacts on said second annular plate, a pin carried by said fixed plate and engaging in the slots on said annular plates to prevent relative rotation between said plates and between either of said plates and said fixed plate and a key adapted for insertion through said sleeve to displace said pin out of its locking position, rotation of said key after displacement of said pin permitting relative displacement of said annular plates and relative displacement of either of said plates with said fixed plate.

4. An electric switch as claimed in claim 3, comprising wards on said key and a pair of centrally slotted discs at the inlet end of said sleeve for the passage of the key ward therethrough, the lower of said discs when the wards are in position in the slots therein connecting said key with said sleeve to rotate one of said relatively annular displaceable plates.

5. An electric switch as claimed in claim 3 comprising a bolt situated in said sleeve and a radially disposed arm at one end of said bolt for connection to said pin, the insertion of said key and the contact thereby with the other end of the bolt longitudinally displacing said bolt to release said pin in locking engagement between said relatively displaceable annular plates.

6. An electric switch as claimed in claim 3, comprising a bolt within said sleeve, spring means operating said bolt, a radially disposed arm carried by said bolt and engaging with said pin, the insertion of said key within said housing forcing said bolt against said spring to release said pin from engagement between said relatively displaceable annular plates.

7. An electric switch having two concentric switch plates each provided at its edges with grooves, two of which are in register

for each switch position, means for operating said switch plates, and locking means operated by one of said operating means and adapted to engage in said grooves when they are in register.

8. An electric switch having two concentric switch plates each provided at its edges with grooves, two of which are opposite each other for each switch position, a key for operating one of said switch plates, a handle for operating the other switch plate, and a pin axially movable by the key and engaging in opposing grooves.

9. An electric switch including a key, a switch handle provided with a recess in the axis thereof, and a rotatable switch member, said switch adapted to be locked by the withdrawal of said key from said recess and unlocked when said key is pressed inwardly of said recess, said key being coupled with said rotatable switch member when pressed inwardly whereby rotation of said key rotates said rotatable switch member.

In testimony whereof I have hereunto affixed my signature.

HERMANN STEINHART.
